UNITED STATES PATENT OFFICE.

GEORGE HILLARD BENJAMIN, OF NEW YORK, N. Y.

SYSTEM OF AUTOMATIC BLOCK-SIGNALING FOR RAILWAYS.

Specification of Letters Patent. Patented Nov. 16, 1915.

1,160,129.

Application filed May 1, 1911. Serial No. 624,280.

To all whom it may concern:

Be it known that I, GEORGE HILLARD BENJAMIN, a citizen of the United States, residing at the city, county, and State of New York, and whose post-office address is 66 Broadway, New York city, New York, have invented certain new and useful Improvements in Systems of Automatic Block-Signaling for Railways, of which the following is a specification.

My invention consists in a system of block signaling which may be employed in connection with steam or electric railways.

The object of my invention is primarily to increase the factor of safety in signaling, by separating the conductors for the propulsion and signaling currents, thereby doing away with expensive track insulations, reactance bonds, plurality of signaling generators, and the like.

The accompanying diagrams will serve to illustrate my invention, in which—

Figure 1 shows my invention as applied to an electric railway; Fig. 2 shows my invention as applied to a steam railway; Fig. 3 is a transverse section through one side of a vehicle, showing an inductive coil on the vehicle and wayside inductive coils along the trackway.

I wish it understood that the diagrams are merely illustrative of the general principles involved, and are not in any wise intended to show all the various features of construction which may be employed, as owing to the present state of the art, such details may be left to the skill of those familiar with the art.

In the drawings, 5 indicates a source of propulsion current, shown as a direct current generator. It may, however, be an alternating current generator. 6, feeder conductor, which may be an overhead wire or third rail. 7—8 traffic rails, which are collectively connected to one terminal of the propulsion generator 5. The track rails are shown as continuous, that is, they are made up of ordinary rail sections connected by bonds as in any steam or electric railway. 9, source of signaling current, which is preferably an alternating current generator. In the system described, it is immaterial whether the frequency of the current produced by the signaling generator be the same or different from that produced by the propulsion generator 5, as the track and signal circuits are quite distinct. 11—12, signaling

feeders. 13, energy transformers arranged at block intervals along the trackway and having their primary coils 14, connected across the feeders 11—12. Arranged along the trackway is a channel iron 15 which serves as a conductor, carried by supports 16 (Fig. 3). Located within the cavity of the channel iron are wayside coils of wire 17, which may be given any required length or number of turns. The secondary 18 of energy transformer 13, is connected at one terminal 19, to the channel iron 15, and at its other terminal 20, to a conductor 21. One terminal of each of the wayside coils 17 is connected to the conductor 21, and the opposite terminal to the channel iron 15. In other words, the coils 17, which for the purpose of description, I term the wayside coils, are connected across the conductors 15 and 21 in parallel. Located in the conductor 21 and between pairs of the wayside coils, are reactances 22 which have for their purpose to divide the current from the secondary 18 between the wayside coils 17.

The conductor 21 (Fig. 1) is divided into sections corresponding to the length of the block sections A, B, C.

In Fig. 2, the secondary 18 is shown as having its terminal 19, connected to the rail 8, which is continuous, and its opposite terminal 20 to adjacent channel irons 15 and 15^a, the channel iron in this figure being divided into sections with the reactances between pairs of channel irons.

In each of the figures, four wayside coils 17 constitute a block section, such as A, B, C. Located in each block section is a signal 23, and at each end of the block sections are signal controlling devices 24, connected through one terminal 25 to the channel iron 15, and through opposite terminal 26 to the conductor 21; and in Fig. 2, one terminal to the rail 8, and the other terminal to a section of the channel iron. The magnets are provided with armatures 27 connected in series in local circuits 28, as is the usual practice. It will be observed that the energy transformer 13 feeds into the middle of the block section, that is, to the terminals of the two central wayside coils, and that the signal controlling devices 24 are at opposite ends of the block section. By reason of this arrangement a vehicle entering a block from either end will deenergize the adjacent relay, and cause the signal to move to the "danger" position.

29 represents a motor vehicle. Mounted on the motor vehicle is a coil 30 which is closed upon itself and arranged so as to be moved in close relation to the wayside coils 17 (see Fig. 3). Preferably the arrangement should be such that the coil 30 will move parallel to the wayside coils 17 and with as small an air gap as is possible.

The operation of my improved system 10 will be readily understood from the foregoing description. Normally, the current induced by energy transformer 13, flows through several wayside coils 17 in parallel, and the reactance of these coils maintains a 15 certain difference of potential between the channel iron 15 and the conductor 21, in the arrangement of Fig. 1, and in Fig. 2 between the channel sections 15, 15^a and the rail 8. The signal controlling devices 24, 20 are shunted about the wayside coils 17 at each end of the block, and are energized by the current due to the difference of potential maintained between its terminals by the reactance as above explained. Normally, 25 therefore, the armatures 27 are attracted, and the local signal circuits 28 are closed, thereby maintaining the signals in the "clear" position.

When a vehicle moves into a block section, carrying its coil 30 into close inductive relation with the wayside coils 17, successively the reactive influence of the short-circuited coil 30 has the same effect upon a wayside coil 17, as a closed secondary has 25 upon the primary of a transformer. In other words, the opposite magnetic flux set up in the closed coil 30, reacts upon the magnetic field of the wayside coil 17, and nullifies its reactance, thereby cutting down 30 the potential between the terminals of the coil 17 and reducing the current in the signal controlling device 24, below the holding value, so that the local circuit will be opened and the signal will move to the "danger" 35 position. When the coil 30 is adjacent one of the intermediate wayside coils 17, nullifying its reactance in the manner described, the coil becomes practically a short-circuit across the terminals of the energizing trans- 40 former. Inasmuch as the coil 30 moves into reactive influence with the succeeding wayside coil 17 before it has moved out of inductive relation with the preceding coil, the signal will be maintained in the "danger" 45 position as long as the car is in the block section.

I do not limit myself in any wise to the size and character of the coil mounted upon the vehicle or the wayside coils mounted 60 along the trackway, as it will be manifest to those skilled in the art, that very many arrangements may be made which will carry out the intent of the invention. Further, I do not limit myself in any wise to the 65 character of the reactance devices employed

to divide the signaling current between the wayside coils 17, nor to the character of the signal controlling devices 24. Such devices may be ordinary tractive relays, single phase, polyphase, or other forms of motor 70 well known to art.

It will be observed that in Fig. 1 the trackway is entirely distinct from the signaling system, and that no signaling current flows through the rails. In Fig. 2 on the other hand, one rail is used as a part of 75 the signaling circuit. This of course is not at all essential, but is merely shown for the purpose of illustration, and further, to indicate that there may be combined with a 80 system such as disclosed, means for indicating a broken rail, for it is plain that if the rail 8 should break, the signal would be carried to the "danger" position.

Having thus described my invention, I 85 claim:

1. A system of block signaling, comprising a trackway, a motor-vehicle on said trackway, a coil closed upon itself carried by the vehicle, a source of signaling current, 90 a number of conductors energized from the source of signaling current, one of said conductors divided into lengths corresponding to a block section, a number of wayside coils connected in parallel across said conductors 95 and said coils arranged along the trackway in inductive proximity to the coil carried by the motor vehicle, signal controlling devices connected across two of said conductors and in shunt of said wayside coils, and signals 100 controlled by said devices.

2. A system of block signaling, comprising a trackway, the rails of which are continuous, a motor vehicle on said trackway, a coil closed upon itself carried by the vehicle, a source of signaling current, a series 105 of wayside coils energized from parallel connections to said source of signaling current, and said coils arranged along the trackway in inductive proximity to the coil carried by the motor vehicle, signal controlling devices connected in shunt across the opposite 110 ends of the series of wayside coils and signals controlled by said devices.

3. A system of block signaling, comprising a trackway, a motor vehicle on said trackway, a coil closed upon itself carried by the vehicle, a source of signaling current, a series of wayside coils energized from parallel connections to said source of signaling 115 current and arranged in groups along the trackway and in inductive proximity to the coil carried by the motor vehicle, and each group forming a block; signal controlling devices connected in shunt 120 across the ends of each group of coils and signals controlled by said devices.

4. A system of block signaling, comprising a trackway, a motor vehicle on said trackway, a coil closed upon itself carried 125

- by the vehicle, a source of signaling current, 5
 transformers having their primary terminals connected to the source of signaling current, a series of wayside coils connected in parallel across the terminals of the secondary of each transformer, and each of said series constituting a block section and in inductive proximity to the coil carried by the motor vehicle, signal controlling devices connected in shunt across the end coils of each group and signals controlled by said devices.
5. A system of block signaling, comprising a trackway, a motor vehicle on said trackway, a coil closed upon itself carried by the vehicle, a number of conductors connected to the source of signaling current, a series of wayside coils connected in parallel across said conductors, and said coils arranged along the trackway in inductive proximity to the coil carried by the motor vehicle, signal controlling devices connected in shunt of said coils, and signals controlled by said devices.
10. 6. A system of block signaling, comprising a trackway, a motor vehicle on said trackway, a coil closed upon itself carried by the vehicle, a source of signaling current, a number of conductors, a transformer having its primary terminals connected to the source of signaling current and its secondary terminals to the two conductors at about their centers, a series of wayside coils connected in parallel in pairs across said conductors on opposite sides of the points of connection of the secondary of the transformer to the conductors, and said coils arranged along the trackway in inductive proximity to the coil carried by the motor vehicle, signal controlling devices connected in shunt of said coils, one of such devices on each side of the point of connection of the terminals of the secondary to said conductors, and signals controlled by said devices.
15. 7. A system of block signaling, comprising a source of propulsion current, a feeder therefrom, a trackway of which the rails are continuous, a motor vehicle on said trackway, a coil closed upon itself carried by the vehicle, a source of signaling current, a number of conductors energized by said source of signaling current, a series of wayside coils connected in parallel across said conductors and said coils arranged along the trackway in inductive proximity to the coil carried by the motor vehicle, signal controlling devices connected in shunt of said coils, and signals controlled by said devices.
20. 8. In a block signaling system, the combination of a source of propulsion current, a trackway of which the rails are continuous, a motor vehicle on said trackway, a coil closed upon itself carried by the vehicle, a source of signaling current, wayside coils arranged in groups and energized from parallel connections to said source of signaling current, and said coils arranged along the trackway in inductive proximity to the coil carried by the motor vehicle, signal controlling devices connected in shunt of said coils, and signals controlled by said devices.
25. 9. In a block signaling system, the combination of a source of propulsion current, a trackway of which the rails are continuous, a motor vehicle on said trackway, a coil closed upon itself carried by the vehicle, wayside coils energized from parallel connections to said source of signaling current, arranged in groups along the trackway to form block sections, and said coils located in inductive proximity to the path traversed by the closed coil on the motor vehicle, signal controlling devices connected in shunt of said coils and normally energized by the difference of potential excited between the terminals of the coils, whereby they will be respectively deenergized when the closed coil carried by the motor vehicle moves into proximity to a corresponding one of the wayside coils of the group, and signals controlled by said devices.
30. 10. In a block signaling system, the combination of a trackway, a motor vehicle on the trackway, a coil carried by the vehicle, a source of signaling energy, transformers having their primary terminals connected across the source of signaling energy, a number of conductors connected respectively to the terminals of the secondary of each transformer, wayside coils connected in parallel across the conductors and said coils arranged along the trackway in inductive proximity to the coil carried by a motor vehicle, signal controlling devices connected in shunt with the coils and normally actuated by the difference of potential of the signaling current at the terminals of said coils, and signals controlled by said devices, whereby when said coils move into proximity to any one of said coils, the reactance of said wayside coil is changed and the difference of potential across its terminal is consequently changed and a signal controlling device affected.
35. 11. A system of block signaling, comprising a source of propulsion current, feeders therefrom, a trackway having the rails continuous, a motor vehicle on said trackway, a coil closed upon itself carried by the vehicle, a source of signaling current, a number of conductors connected to the source of signaling current, a series of wayside coils connected in parallel across said conductors, disposed along said trackway but separated therefrom and in inductive proximity to the coil carried by the motor vehicle, when said coil is moved along the trackway, signal controlling devices normally energized by the difference of potential at the terminals of said wayside coils,

- but adapted to be deenergized when the coil on the motor vehicle moves in inductive proximity to one of the corresponding coils, and signals controlled by said devices.
- 5 12. A system of block signaling, comprising a coil closed upon itself carried by a motor vehicle, a source of signaling current, a series of wayside coils connected in parallel across the source of signaling current 10 and disposed in a position to be successively put into inductive relation with the coil carried by the motor vehicle, signal controlling devices normally energized by the difference

of potential between the terminals of the wayside coils arranged in parallel whereby 15 they will be respectively deenergized when the coil carried by the motor vehicle and one of the corresponding wayside coils are in inductive relation, and signals controlled by said devices.

In testimony whereof, I affix my signature, in the presence of two witnesses.

GEORGE HILLARD BENJAMIN.
